HIS ATTORNEYS

UNITED STATES PATENT OFFICE

CLARE A. WETZELL, OF STERLING, ILLINOIS

TOP

Application filed December 18, 1931. Serial No. 581,973.

This invention relates to certain novel improvements in tops, and has for its principal object the provision of an improved construction of this character which will be entertaining in use and economical to manufacture.

I am aware that in the toy maker's art various types of spring-rotated tops are known and likewise various types of spinning heads and trigger mechanisms for releasing the tops from the spinning heads in the act of spinning the tops. All of these devices of the prior art, however, pertain to means for spinning a single top and there has not heretofore been known or provided a device

10 which will simultaneously spin a group or plurality of spring-wound tops.

It is, therefore, the primary object of this invention to provide new and novel means for accomplishing the novel result of simultaneously spinning by mechanical means a group or plurality of spring-wound tops.

Other objects of the invention are: To provide a new and unique spinning head common to and for winding a plurality or group of spring-wound tops; and to provide a new and unique combination of the said spinning head with a trigger mechanism by means of which, in a simple operation, a group or plurality of spring-wound tops may be simultaneously released from the spinning head in the act of spinning the tops.

Other objects will appear hereinafter.

The invention consists in the novel combination and arrangement of parts to be hereinafter described and claimed.

The invention will be best understood by reference to the accompanying drawing showing the preferred form of construction, and in which:

40 Fig. 1 is a perspective view of a practical embodiment of the invention;

Fig. 2 is a sectional view on line 2—2 in Fig. 1;

45 Fig. 3 is a bottom plan view of the spinning head on line 3—3 in Fig. 2;

Fig. 4 is a top plan view of the spinning head on line 4—4 in Fig. 2; and

50 Fig. 5 is a perspective detailed view of a conventional type of top that is employed to illustrate the invention.

In the drawing, which represents a preferred and practical embodiment of the invention, I have illustrated the invention as employing a group of two tops 10 of conventional design, each having a body 11 and a 55 stem 12; although it is to be understood that I do not limit the invention to a group of two tops but may, with such modifications in structure as will come within the scope of the appended claims, employ a group of a 60 larger number of tops. The tops 10 illustrated may be made of any suitable material and be of any desired design.

My invention includes spinning head 13 which provides a common support for the group of tops 10 and this head 13 may be made of any suitable material such as, for example, wood or metal and be of any desired shape.

65 In the head 13 there are provided passages 14 for the top winding springs 15, each of which has an end portion attached to the head 13 as at 16. The spinning head 13 is provided with passages 17 in each of which is a spring-actuated pin 18; the pins 18 being urged by springs 19 into bearing engagement with caps 20 attached to the bodies 11 of the tops 10. In each of the caps 20 a series of radially arranged recesses 21 is provided and the pins 18 are urged by the 70 springs 19 to dispose the outer end portions of the pins in these recesses to hold the tops in engagement with the spinning head during and after completion of the winding of the springs 15 with the tops 10 and the head 75 13 are assembled and the hooked ends 22 of the springs 15 are engaged in preselected recesses 21 in the caps 20.

80 Attached to the spinning head 13, or formed integrally therewith as desired, is a finger grip 23 in which is provided a passage 24. Movable associated with the finger grip 23 by being slidably mounted in the passage 90 24 is a plunger or trigger 25 for releasing the tops 10 as a group from the spinning head 95 after the completion of the winding operation. Movable by the trigger 25 by being attached thereto is a member 26 which is movable in a slot 27 in the finger grip 23 and the outer end portions 26a of the member 26 bear 100

upon the top stems 12 whereby the group of tops 10 may be simultaneously released as a group from the spinning head, after the completion of the winding operation, by pressing with the thumb or finger upon the trigger 25 while holding the finger grip 23 in the hand; thus simultaneously spinning a group of tops by means of a single operation and creating an effect that is both novel in 10 the art and entertaining.

It is evident that by lengthening the member 26 and the common support or spinning head 13 and by providing additional springs 15 and associated parts the number of tops 10 that may be mounted in the spinning head or common support 13 and simultaneously released as a group therefrom may be increased to any number desired.

While I have illustrated and described the 20 preferred form of construction for carrying my invention into effect, this is capable of variation and modification without departing from the spirit of the invention. I, therefore, do not wish to be limited to the precise 25 details of construction set forth, but desire to avail myself of such variations and modifications as come within the scope of the appended claims.

Having thus described my invention, what 30 I claim as new and desire to protect by Letters Patent is:

1. A toy comprising a spinning head for a group of tops, each including a stem, spring means carried by the head for winding the 35 tops, said head including a portion providing a finger grip, means for holding the tops on the head during and after completion of the winding operation, and a trigger mechanism including a member slidably mounted 40 in said finger grip and operable upon said stems for simultaneously releasing the tops from the head in the act of spinning the tops.

2. A toy comprising a common support for a group of tops each including a stem, spring 45 means carried by the support for winding the tops, means for holding the tops on the support during and after completion of the winding operation, a finger grip on the support having a slot formed therein, a trigger 50 movably associated with the finger grip, and a member attached to the trigger slidably in said slot and operable upon said trigger to disengage the tops simultaneously from said holding means during the act of spinning the 55 tops.

3. In a toy, the combination of a top spinning head, a group of spring-wound tops each including a stem, an individual spring winding mechanism for each of said tops, 60 said mechanisms being carried by and spaced apart on said head, means for holding each of said tops on the spinning head during and after completion of the winding operation, and a trigger release mechanism carried by 65 said head and common to all of the tops in

said group, said trigger mechanism including elements operable simultaneously upon said stems for releasing said tops as a group from the spinning head during the act of spinning the tops.

4. In a toy, the combination of a top spinning head having a plurality of spaced apart 70 passages provided therein, an individual top spring winding mechanism in each of said passages, a group of spring-wound tops each including a stem and said stems being receivable in said passages within said winding mechanisms, means for holding each of said tops on the spinning head during and after 75 completion of the winding operation, and a trigger release mechanism carried by said head and common to all of the tops in said group, said trigger mechanism including elements operable simultaneously upon said stems for releasing said tops as a group from the spinning head during the act of spinning the tops.

5. In a toy, the combination of a top spinning head having a plurality of spaced apart 80 passages provided therein, an individual coil 85 spring top winding mechanism in each of said passages, a group of spring-wound tops each including a stem, said stems being receivable in said passages within said coil spring mechanisms and each having a portion adapted to project out from the corresponding passage beyond said head, means for holding each of said tops on the head during and after completion of the winding operation, and a trigger release mechanism carried by said head having elements operable upon said projecting stem portions for releasing said tops from 90 said head during the act of spinning the tops.

6. In a toy, the combination of a top spinning head having a plurality of spaced apart 95 passages provided therein, an individual coil 100 spring top winding mechanism in each of said passages, a group of spring-wound tops each including a stem, said stems being receivable in said passages within said coil spring mechanisms and each having a portion adapted to project out from the corresponding passage beyond said head, means for holding each of said tops on the head during and after completion of the winding operation, said head including a portion having a slot formed 105 therein, and a trigger release mechanism for said tops, said trigger mechanism including a plunger slidably mounted in said slot and elements attached to and projecting from said plunger, said elements being adapted to bear upon said projecting stem portions for simultaneously releasing said tops as a group from 110 said head during the act of spinning the tops.

In testimony whereof I affix my signature. 115
CLARE A. WETZELL.
